UNITED STATES PATENT OFFICE.

CLEMENT C. SMITH, OF WHEELING, WEST VIRGINIA.

CAR-DUMPING PLATFORM.

Application filed June 8, 1921. Serial No. 475,888.

To all whom it may concern:

Be it known that I, CLEMENT C. SMITH, a citizen of the United States of America, and resident of Wheeling, county of Ohio, and State of West Virginia, have invented certain new and useful Improvements in Car-Dumping Platforms, of which the following is a specification.

This invention relates broadly to car-dumping mechanism, and it has for its primary object to provide a platform, designed primarily for the dumping of mine cars, which is adapted to be automatically actuated, when mounted by a loaded car, to assume inclined car-dumping position, and which is adapted, following the dumping operation, to resume its normal position.

A further object of the invention is to provide a platform having, in general, the characteristics of the dumping platform disclosed in Patent No. 1,380,745, granted to me June 7, 1921, to which reference is had for a description of the principle by which the platform and car, following dumping of the latter, are returned to normal position through shifting of the location of the center of gravity.

A still further object is to provide simple adjusting means whereby the point of arrest of cars mounting the platform may be accurately adjusted.

In describing the invention in detail, reference is herein had to the accompanying drawings, in which—

Figure 1 is a side elevation of the invention with a car mounted thereon;

Figure 2 is a broken top plan view of the invention;

Figure 3 is an enlarged detail view in top plan of the adjusting device;

Figure 4 is a side elevation of the same; and—

Figure 5 is a section on line 5—5, Fig. 1.

Referring to said drawings, 1 indicates parallel longitudinally extending beams or timbers of a tipple structure. Carried by the tipple are track rails 2 which are disposed in registering alinement with the rear ends of rail sections 3 carried by a tilttable or rockable dumping platform 4. Rigidly mounted upon the top of the platform at each of its opposite sides is an upright frame member or hanger 5 which carries an outwardly directed spindle 6. Each of the spindles is journaled in a bearing 7 formed on or carried by an upright frame member

or support 8 which is mounted upon and supported by the adjacent timber 1. Thus, it will be apparent that the platform 4 is suspended from the bearings 7 of the supports 8 by the spindles 6 and depending hangers 5, rendering said platform capable of being swung or rocked on said spindles to and from its normal horizontal position.

Suitable means is provided whereby rearward tipping of the platform from its normal horizontal position is prevented, said means, as herein exemplified, comprising a vertically adjustable bolt 9 mounted in a supporting bracket 10 carried on the inner face of each timber 1, said bolts being adapted for adjustment to an elevation in which their heads constitute rests for the rear end of the platform, as shown in dotted lines in Fig. 1.

The rail sections 3 have their front ends bent upwardly in arcuately curved form, as shown at 3^a, and carried by each of said curved ends 3^a is a wheel chock comprising a bar 11 having a toothed face. The upper end of each of said curved rail ends 3^a has one side of its head and base portions removed to substantially the plane of the web throughout a suitable distance, leaving only a slightly projecting rib 12, as shown in Figs. 3 and 4, adapted to engage a tooth of the chock 11. Said chock has therein a longitudinal slot 13 through which the rail web is directed one or more bolts 14 whereby said chock is secured in adjusted position. As is obvious, said chocks may be adjusted forward or back with respect to the rail ends 3^a as may be required to arrest cars which mount the platform approximately at the point at which the center of gravity of the platform and car is in a vertical plane intersecting the axes of the spindles 6.

From the foregoing it will be understood that, when a loaded car mounts the platform and its front wheels engage the chocks 11 with considerable force, as ordinarily, the momentum is sufficient to carry the car and platform from the normal horizontal position shown in full lines in Fig. 1 to the inclined dumping position indicated in dotted lines in said figure, in which the load is discharged from the car by gravity. In swinging or rotating forward on the spindles 6, the center of gravity of the platform and loaded car, which is located above the level of said spindles and which should, theoretically, be located approximately in a vertical

plane intersecting the axes of said spindles, as shown at *a* in Fig. 1, advances to a point, indicated at *a'* in said figure. However, when the load shall have been dumped, the 5 center of gravity of the platform and empty car will have shifted to a point *b'* located below and rearward of such vertical plane, by reason of which said platform and car will promptly be returned to their normal 10 horizontal position in which the center of gravity is located at *b* approximately in said vertical plane.

What is claimed is—

1. The combination with a tipple structure, of a car-dumping mechanism comprising a dumping platform, a pair of supporting members mounted on said structure at opposite sides of said platform, hangers journaled on and depending from said members, said platform being carried by said hangers, rail sections carried by said platform, and wheel chocks located adjacent to the front ends of said sections and means for adjusting the positions of said chocks.
2. The combination with a tipple structure, of a car-dumping platform having thereon rail sections for receiving cars to be dumped, supports provided on the tipple structure at opposite sides of said platform, adjustable rests for the rear end of said platform, hangers pivoted upon and depending from said supports, said platform being carried by said hangers, wheel chocks associated with said rail sections and means for adjusting the position of said chocks, the pivotal connections between said hangers and said supports being located below the level of the center of gravity of the platform with a loaded car mounted thereon against said chocks and above the level of the center of gravity of said platform with an empty car occupying said position, and also being located approximately in a vertical plane intersecting said centers of gravity.

3. The combination with a tipple structure, of a car-dumping platform having thereon rail sections for receiving cars to be dumped, supports provided on the tipple structure at opposite sides of said platform, hangers pivoted upon and depending from said supports, said platform being carried by said hangers, wheel chocks associated with said rail sections, and means for adjusting the positions of said chocks, the axis upon which said platform swings being located below the level of the center of gravity of the platform with a loaded car mounted thereon against said chocks and above the level of the center of gravity of said platform with an empty car occupying said position, said axis also being located approximately in a vertical plane intersecting said centers of gravity.

4. The combination with a tipple structure, of a car-dumping platform having thereon rail sections for receiving cars to be dumped, supports provided upon the tipple structure at opposite sides of said platform, hangers pivoted upon and depending from said supports, said platform being carried by said hangers, wheel chocks associated with the front ends of said rail sections, and adjustable rests for the rear end of said platform, the axis of rotation of said platform being located below the center of gravity of the platform with a loaded car mounted thereon against said chocks and above the center of gravity of said platform with an empty car occupying said position, said axis also being located approximately in a vertical plane intersecting said centers of gravity.

In testimony whereof, I affix my signature in presence of two subscribing witnesses.

CLEMENT C. SMITH.
